Below this is located a second scroll on either side extending along the outline of the handle, and beneath this a third scroll to the end of the handle. In the upper end of the bowl is a shell like ornament and from this scrolls are on either side terminating in leafy projections extending toward the center of the bowl. On the rear face of the handle at the top is a shell like ornament, while on each edge of the outline of the spoon is a series of scrolls to the base of the handle.
